(57) **CLAIM**

The ornamental design for a display hanger for a shower curtain rod, as shown and described.

DESCRIPTION

FIG. 1 is a perspective view of an embodiment of a display hanger for a shower curtain rod according to my new design; FIG. 2 is a front elevation view thereof;

FIG. 3 is a rear elevation view thereof;

FIG. 4 is a right side elevation view thereof, the left side being a mirror image thereof;

FIG. 5 is a top plan view thereof;

FIG. 6 is a bottom plan view thereof;

FIG. 7 is a perspective view of another embodiment of a display hanger for a shower curtain rod according to my new design;

FIG. 8 is a front elevation view thereof;

FIG. 9 is a rear elevation view thereof;

FIG. 10 is a right side elevation view thereof, the left side being a mirror image thereof;

FIG. 11 is a top plan view thereof; and,

FIG. 12 is a bottom plan view thereof.

The broken lines shown herein for illustrative purposes of the environment or which define the bounds of the claimed design form no part of the claimed design.
